A. C. CHRISTOPHERSON

SHEET FEEDER

Filed Feb. 2, 1925

UNITED STATES PATENT OFFICE.

ALFRED C. CHRISTOPHERSON, OF CHICAGO, ILLINOIS, ASSIGNOR TO HACKER MANUFACTURING CO., OF CHICAGO, ILLINOIS, A CORPORATION OF ILLINOIS.

SHEET FEEDER.

Application filed February 2, 1925. Serial No. 6,410.

My invention relates to sheet feeders employing feed boards and side guides, such as are employed, for example, in connection with printing presses.

5 The invention has for one of its objects the provision of means whereby the side guides may be restored to the positions selected for them, whereby the runs of sheets may be interrupted to permit the running of 10 sheets of other sizes and may thereafter be resumed, there being cooperating indices whereby the side guides may be quickly and accurately restored to the positions selected for them.

15 With a printing press equipped with a device of my invention a given run of sheets may be interrupted to permit sheets of another size to be run through the press, the side guide being adapted to be quickly restored to its carefully selected position when 20 the first run is to be resumed, the press thus not being required to remain idle in order to maintain the accuracy of the adjustment of the side guide in event that a given run 25 is to be discontinued for any reason.

The invention has other characteristics and will be fully set forth in connection with the accompanying drawing illustrating the preferred embodiment thereof, and in which 30 Fig. 1 is a side view of a proof press equipped with a sheet feeder of my invention, parts being broken away and shown in section; Fig. 2 is a sectional view on a larger scale on line 2—2 of Fig. 1; Fig. 3 is a plan view, and Fig. 4 is a sectional view, on a larger scale, on line 4—4 of Fig. 2.

35 The press illustrated includes a flat reciprocating bed 1 and a cylinder 2 which is rotated by any suitable means, the cylinder 40 illustrated being operated by a hand crank 3, the bed being in gear with the cylinder.

The cylinder is equipped with grippers 4 carried upon a shaft 5 and opened and closed by means of the arm 6 fixed upon the shaft, 45 a cam 7 which elevates the grippers through the intermediation of the arm, and a roller 8 that is upon the arm and directly engaged by the cam, there being a spring 9 which presses the roller 8 upon the cam and which 50 closes the grippers when the cam is moved out of engagement with the roller.

The feeder includes a feed board 9' including as a part thereof an extension 10.

The feed board has a slot 11 extending crosswise thereof and formed in its extension 10 55 Any usual or suitable guides 12 are carried by the cylinder to determine the extent to which the sheets 13 may be fed forwardly.

A side guide 14 extends above the top surface of the board, this guide having a 60 yoke 15 extending into the slot 11 whereby the guide may be directed in its adjusting movement crosswise of the board. The guide 14 desirably has an extension 15' secured thereto and spaced sufficiently apart from 65 and above the board to permit the sheets to be tucked between the same and the board as they are moved against the guide, the extension 15' preventing the sheets from curling. A threaded rod 16 extends crosswise of the board and underlies the slot 11, this rod being mounted to turn in the bearings 17, 18 and 19, which are carried by and depend from the board extension 10. The yoke 15 of the side guide is in threaded 70 engagement with the threaded portion of the rod, and the rod carries an adjusting knob 20 by which it may be turned, this rod engaging one end of the board extension 10. The rod has a reduced end 21, the shoulder 75 upon the rod at its reduced end engaging one side of the bearing 19, which bearing serves as a stop to take end thrusts of the rod. A spring 22 is coiled about the rod and presses at one end against the opposite 80 side of the bearing 19, that acts as a stop, and against a head 23 upon the rod, whereby the rod is yieldingly held in a fixed plane 85 of rotation. One long side of the slot 11 is provided with a scale 24 with which one 90 side face of the guide 14 may cooperate to indicate the position to which the guide is adjusted. If a notation is kept of this location, a given run of the press may be interrupted and the guide may be given another 95 adjustment to suit the new run, whereafter the guide may be re-adjusted to its original position for the resumption of the original run. The threads upon the rod are very fine so that the adjusting movements of the guide are micrometric. If desired, the knob 20 may be provided with a scale 24' 100 around its periphery to be transverse of the rod and adjacent the board which may have an index line 25 cooperating with the scale 105 24' so that the position to which the rod is

turned may be noted, an arrangement permitting the most accurate restoration of the guide 14 to any selected position.

Changes may be made without departing 5 from the invention.

Having thus described my invention I claim:

1. In a sheet feeder, the combination with a feed board; of a rotatable rod assembled 10 with the board and arranged transversely of the board beneath the latter and accessible for operation at one side of the board; and a side guide at the opposite side of the board and in threaded connection with the 15 rod and extending above the board within the side limits of the latter, whereby the rod, upon being turned, causes the side guide to be moved transversely of the board, there being a scale upon one of these latter two 20 elements arranged transversely of the board and a cooperating index upon the other of these two elements to indicate the extent to which the side guide is moved by the rod transversely of the board.
2. In a sheet feeder, the combination with a feed board; of a rotatable rod assembled 25 with the board and arranged transversely of the board beneath the latter and accessible for operation at one side of the board; and a side guide at the opposite side of the board and in threaded connection with the rod and extending above the board within the side limits of the latter whereby the rod, upon being turned, causes the side guide 30 to be moved transversely of the board, there being a scale upon one of these latter two elements arranged transversely of the board and a cooperating index upon the other of these two elements to indicate the extent to 35 which the side guide is moved by the rod transversely of the board, there being also a scale and cooperating index provided upon the rod and board to indicate the position to which the rod is turned.

which the side guide is moved by the rod 40 transversely of the board, there being also a scale and cooperating index provided upon the rod and board to indicate the position to which the rod is turned.

3. In a sheet feeder, the combination with a feed board; of a rotatable rod assembled 45 with the board and arranged transversely of the board beneath the latter and accessible for operation at one side of the board; and a side guide at the opposite side of the board and in threaded connection with the rod extending above the board within the side limits of the latter whereby the rod, upon being turned, causes the side guide to be moved transversely of the board, there being a scale and cooperating index provided upon the rod and board to indicate the position to which the rod is turned.

4. In a sheet feeder, the combination with a feed board; of a rotatable rod assembled 50 with the board and arranged transversely of the board and accessible for operation at one side of the board; a side guide at the opposite side of the board and in threaded connection with the rod whereby the rod, upon being turned, causes the side guide to be moved transversely of the board; there being a scale upon one of these latter two 55 elements arranged transversely of the board and a cooperating index upon the other of these two elements to indicate the extent to which the side guide is moved by the rod transversely of the board; a stop for receiving end thrusts of the rod; and a 60 spring holding the rod against said stop.

In witness whereof, I hereunto subscribe my name.

ALFRED C. CHRISTOPHERSON
